COMBINATION TISSUE DISPENSER AND DISPOSAL CONTAINER

John A. Bott, 931 Lakeshore Drive,
Grosse Pointe Shores, Mich.

Filed Dec. 12, 1960, Ser. No. 63,192

Term of patent 14 years

Figs. 2, 3, 4, 5, 6 and 7 are, respectively, top plan, left end elevational, right end elevational, bottom plan, rear elevational and perspective views of the article shown in Fig. 1.

I claim:

The ornamental design for a combination tissue dispenser and disposal container, as shown.
